UNITED STATES PATENT OFFICE.

IZAK V. ARVONEN, OF CALUMET, MICHIGAN.

DESIGN FOR A FRAME FOR PICTURES.

SPECIFICATION forming part of Design No. 28,060, dated December 21, 1897.

Application filed October 18, 1897. Serial No. 655,628. Term of patent 7 years.

To all whom it may concern:

Be it known that I, IZAK V. ARVONEN, a citizen of the United States, residing at Calumet, in the county of Houghton and State of Michigan, have invented and produced a new and original Design for a Frame for Pictures and other Objects, of which the following is a specification, reference being had to the accompanying drawing, forming a part thereof, which represents a plan view of a picture-frame embodying my design.

The leading feature of the design consists of a floral wreath A, apparently resting upon a second and larger scroll-wreath B. The scroll is of the ribbon type, the ribbon being

so folded as to present a series of loops b. Other features of the design consist in stars connected with the floral wreath A, an ornamental inner border C, the representation of a flag D, located at the upper portion of the scroll-wreath, and the representation of an eagle perched upon the staff of the flag. 20

I claim—

The design for a frame for pictures and other objects, herein shown and described.

IZAK V. ARVONEN.
